UNITED STATES PATENT OFFICE.

FRANK WILLIAM MANTON, OF TORONTO, ONTARIO, CANADA.

INKING MEANS FOR PRINTING MACHINES.

Application filed July 7, 1927. Serial No. 204,043.

This invention relates to inking means for printing machines, as described in the present specification and illustrated in the accompanying drawings which form part 6 of the same.

The invention consists essentially of the novel features pointed out broadly and specifically in the claims for novelty following a description containing an explanation in detail of an acceptable form of the invention.

The objects of the invention are to provide efficient means of stopping the rotation of the ductor roller after applying ink to the inking plate of the printing machine; to control the rotation of the ductor roller so that the whole of its periphery or surface will have engaged the fountain roller at equal intervals, or in other words, the ductor 20 roller will receive successive stripes of ink from the fountain roller causing the whole surface of said ductor roller to come into contact with said fountain roller at determined equal intervals; to provide a vibrator 25 roller with the fountain roller ductor; to have means of releasably locking a vibrator roller in a spaced position from its corresponding ductor; and generally, to obtain a better and more uniform distribution of 30 ink upon the inking plate.

In the drawings, Figure 1 is a fragmentary front elevation of a printing press having inking means built in accordance with this invention.

35 Figure 2 is a side view of Figure 1.

Figure 3 is an enlarged fragmentary side view of one of the ductor roller rocker arms.

Figure 4 is an elevation view showing an assembly of various parts of the vibrator 40 roller controlling means.

Figure 5 is a part elevation and part section view of the threaded end of the vibrator roller and its bearing.

Figure 6 is a plan view of the other bearing of the vibrator roller.

Figure 7 is an end view of the collar.

Figure 8 is a section of the spring supporting sleeve.

Like numerals of reference indicate corresponding parts in the various figures.

Referring to the drawings, 10 designates the frame of a typical printing press of the kind to which this invention is applicable, having the extension 11 upon which are 55 mounted the fountain roller 12 and the ink fountain 13. 14 designates the ductor roller

suitably journalled in the rocker arms 15 which pivot on the frame, the rocker arms being suitably controlled to alternately retain the ductor in contact with the fountain 60 roller 12 and in a position to be engaged by the inking plate 16^a, or in some presses the ink distributor roller.

16 is a vibrator roller having the pivot ends 17 rotating in the bearings 18 and 19, 65 these bearings being adapted to slide up and down in the rocker arms and therefore allow the vibrator to contact with or be supported by the ductor 14.

20 is a dog pivotally secured to each of 70 the rocker arms at a point 21 and positioned and sized to engage the vibrator bearings and retain the vibrator out of contact with the ductor, 22 being pins secured to the rocker arms and determining the clockwise 75 rotation of the dogs. The dogs are operated or used to keep the weight of the vibrator from injuring the composition of the ductor when the machine is not operating.

One end of the spindle is finished with a 80 right-hand threaded portion 23 turning in the threaded bearing 18, so that the vibrator 16 is shifted axially one way or the other, according to the direction of rotation of the ductor 14; for instance, as the inking plate 85 16^a moves out or in the direction of the arrow and engages the ductor, rotating the ductor and vibrator in the direction of their respective arrows (Figure 2), the vibrator moves in the direction of the arrow (Figure 90 5); as the inking plate travels back, the direction of rotation of the vibrator is reversed and it travels away from the bearing 18.

The bearing 19 has the stud portion 25 extending towards the centre of the roller 95 16, the stud portion terminating in the reduced portion 26. 27 is a sleeve sized to fit and slide over the stud portion 25; the sleeve has the enlarged or bell portion 28 finished with a clutch-like portion 29 made to engage with a corresponding clutch portion 30 of the collar 31 turning with the roller 16. 32 is an adjustable collar fitted over the stud portion of the bearing 19 and having the pin 33 rigid therewith. 34 is a helical 100 spring fitted over the sleeve 27 and having the ends formed with hooks to engage with the pin 33 and the pin 34^a which is rigid with the sleeve 27, as is best shown in Figure 4.

35 is a collar pinned or otherwise secured to the portion 26 of the sleeve 27 and sized

to fit into the bell-shaped portion 28 of said sleeve, therefore releasably locking the sleeve upon the bearing 19.

Tension is imparted to the spring 34 by twisting or turning the collar 32 upon the bearing, the sleeve being locked against rotation by inserting a pin 37 through the sleeve to engage the shoulder 36 provided in the collar 35.

10 The clutch collar 31 is so adjusted upon the shaft that as soon as it begins to rotate in the direction shown by the arrow in Figure 4, the clutch will operate to wind the spring and this is the relative position of 15 the collar to the corresponding clutch member 29 immediately after the inking plate leaves the ductor roller. It follows then that as soon as the inking plate leaves the ductor, the spring will be twisted or tensioned as well as compressed, the sleeve turning over the bearing and shifting with the roller away from the bearing 18 or towards the bearing 19.

In order to allow the clutch collar 31 to move freely towards the bearing 19, the collar is hollowed in as at 38 and sized to provide sufficient clearance to enclose the collar 35.

39 is a lug provided on each of the fountain bearings and situated and sized to engage the vibrator bearings and lift or space the vibrator from contact with the ductor when the rocker arms are lowered and before the ductor turns with said fountain roller.

40 In the operation of the invention, the rocker arms swing to lower the ductor until it engages with the fountain roller, the vibrator being lifted from the ductor by the engagement of the lugs 39 with the vibrator bearings 18 and 19. The ductor then receives a coat of ink on a fraction of its periphery. The rocker arms then lift until the ductor lies in the path of the inking plate 16^A. As the inking plate moves out and engages the ductor 14, the vibrator 16 is rotated, turning the threaded end 23 of the roller 17 in its threaded bearing 18, shifting the roller and the clutch collar 31 away from the bearing 19. The inking plate then reverses its direction, reversing the direction of rotation of the ductor and vibrator and shifting the vibrator and shaft towards the bearing 19. As the inking plate 45 clears the ductor, the clutch members engage and impart a spiral motion to the sleeve 27, therefore twisting and compressing said spring. The spring is thus twisted and compressed until the momentum of the ductor and vibrator is destroyed, the resiliency imparted to the spring acting to rotate the vibrator back to the position it was in at the moment the inking plate cleared the ductor. The rocker arms lower again and 50

55 a fresh portion or fraction of the ductor re-

ceives a coat of ink which is again applied to the inking plate, as aforesaid.

What I claim is:

1. In a printing press, a movable ductor lowering to engage the fountain roller and rising into the path of the inking plate of said press, a vibrator adjacent said ductor and supported thereby, and means of spacing said vibrator from said ductor when the latter is in contact with said fountain roller.

2. In a printing press, a fountain roller, an inking plate, a movable ductor lowering to engage said fountain roller and rising into the path of said inking plate, rocker arms mounting said ductor, bearings loosely mounted in said rocker arms above said ductor and a vibrator rotating in said bearings and supported by said ductor, and lugs carried by said frame adapted to engage said bearings before said ductor is in engagement with said fountain roller.

3. In inking means for printing presses, a ductor and a vibrator loosely mounted thereabove and rotating therewith, and means for releasably locking said vibrator in a spaced relation to said ductor.

4. In inking means for printing presses, a ductor and a vibrator loosely mounted thereabove and rotating therewith, and a dog mechanism adapted to support said vibrator in a position away from said ductor.

5. In a printing press, a movable ductor lowering to engage the fountain roller and rising into the path of the inking plate of said press, a vibrator mounted above said ductor and supported thereby and shifting axially in alternate directions according to the direction of rotation, means of spacing said vibrator from said director when the latter is in engagement with said fountain roller, and adjustable resilient means of checking the rotation of said vibrator in one direction.

6. In a printing press, a fountain roller, an inking plate, a movable ductor lowering to engage said fountain roller and rising to be engaged by said inking plate, a vibrator mounted adjacent said ductor and supported thereby and shifting axially in alternate directions according to its direction of rotation, means of spacing said vibrator from said ductor when the latter is in engagement with said fountain roller, and adjustable resilient means adapted for destroying the momentum of said ductor and vibrator immediately after said inking plate clears said ductor.

7. In a printing press, a fountain roller, an inking plate a movable ductor lowering to engage said fountain roller and rising to be engaged by said inking plate, a vibrator mounted adjacent said ductor and supported thereby and shifting axially in alternate directions according to its direction of ro-

- tation, means of spacing said vibrator from said ductor when the latter is in engagement with said fountain roller, and adjustable resilient means adapted for gradually 5 destroying the momentum of said ductor and vibrator immediately after the inking plate clears said ductor and rotating said ductor back to the position it is in when said plate clears said ductor as aforesaid.
- 10 8. In inking means for printing presses, a ductor adapted to be engaged by the inking plate of the press, a vibrator mounted adjacent to said ductor and rotating therewith, and adjustable resilient means adapted 15 for gradually destroying the momentum of said ductor and vibrator immediately after the inking plate clears said ductor and rotating said ductor back to the position it is in when said plate clears said ductor as 20 aforesaid.
9. In inking means for printing presses, a ductor adapted to be engaged by the inking plate of the press, a vibrator mounted above said ductor and rotating therewith, 25 adjustable resilient means adapted for gradually destroying the momentum of said

ductor and vibrator immediately after the inking plate clears said ductor and rotating said ductor back to the position it is in when said plate clears said ductor as aforesaid, 30 and a clutch mechanism between said vibrator and resilient means.

10. In inking means for printing presses, a ductor roller adapted to be engaged by the inking plate of said press, a frame supporting said ductor, a pair of bearings slidably mounted in said frame above said ductor, one of said bearings being screw-threaded, the other of said bearings having a stud end, a vibrator roller having one 35 end threaded to engage with said threaded bearing, a clutch member turning with said vibrator, a sleeve slidably mounted on said stud end of one of said bearings and rotatable to a limited extent, said sleeve having a clutch portion adapted to co-act with said clutch member, and a spring secured at the ends to the adjacent bearing and the sleeve, respectively.

Signed at the city of Toronto, this 15th 50 day of June, 1927.

FRANK WILLIAM MANTON.
